His Attorney

UNITED STATES PATENT OFFICE.

MAX BROWN, OF CHICAGO, ILLINOIS.

COLLAPSIBLE SLED.

1,364,423.

Specification of Letters Patent.

Patented Jan. 4, 1921.

Application filed April 17, 1918. Serial No. 229,046.

To all whom it may concern:

Be it known that I, MAX BROWN, a citizen of the United States, and a resident of the city of Chicago, county of Cook, and 5 State of Illinois, have invented certain new and useful Improvements in Collapsible Sleds, of which the following is a specification.

My invention relates to improvements in 10 collapsible sleds, and has for its object the provision of an improved construction of this character which is adapted to be folded in compact form and which is durable and efficient in use.

15 My invention consists in the combinations and arrangements of parts hereinafter described and claimed.

The invention will be best understood by reference to the accompanying drawings 20 forming a part of this specification, and in which,

Figure 1 is a perspective view of a collapsible sled embodying the invention.

Fig. 2 a view showing the same collapsed.

25 Fig. 3 a side view of the sled showing the same partially collapsed.

Fig. 4 a bottom plan view of the same showing the same partially collapsed.

Fig. 5 a detail view of a knee-joint construction employed in the sled.

Fig. 6 an enlarged section taken on line 6-6 of Fig. 5, and

Fig. 7 an enlarged section taken on line 7-7 of Fig. 5.

35 The preferred form of construction as illustrated in the drawings comprises side angle bars 8 and angle runners 9 positioned thereunder and collapsibly connected thereto by means of foldable links 10, there being 40 two sets of said links connecting each side bar and its corresponding runner. Each of said links 10 is pivoted to the corresponding side bar and runner and the members of each pair of said links pivoted together 45 at the point 11. Each link is provided with a shoulder 12 adapted to contact with the corresponding side bar or runner to limit the outward swing thereof, and with a lug or ear 13 adapted to contact with a similar

50 lug or ear on the other link, also to limit the outward swing thereof and stiffen and strengthen the construction. By this arrangement it will be observed that each side bar 8 will be securely and readily supported 55 from the corresponding runner 9 when the

links 10 are swung outwardly as shown in Fig. 1, but that by raising the side bars 8 the links 10 may be readily swung inwardly as indicated in Fig. 3, thus breaking the knee-joint formed and permitting of the collapsing or folding of the side bars onto the runners.

The opposite sets of links 10 have their pivotal joints 11 connected by links 14 which are pivotally connected at their inner ends and each pair of which is provided with a lug 15 adapted to engage a notch 16 to limit the swing of said links and form a knee-joint between the opposite sets of links 10 which when the side bars 8 are 60 collapsed onto the runners 9 assume horizontal and parallel positions as indicated in Fig. 4 and may be readily broken or swung outwardly to permit of the approach of the opposite side bars and runners as indicated 65 in Fig. 4. Likewise the side bars are connected by a similar set of links 17 having lugs 18 engaging notches 19 forming a knee-joint connection between said side bars which may be readily folded as indicated in 70 Fig. 4. By this arrangement, it will be observed that after the side bars have been folded onto the runners, the opposite side bars and runners may be again folded on to each other, thus assembling the parts 75 80 85 into compact form.

The top of the sled consists of two transverse bands or straps 20 of canvas or other suitable material, having one of their ends permanently secured to one of the side bars 8 and the other ends equipped with metallic plates having key hole slots 21 therein adapted to engage studs 22 on the other side bar 8 as shown. Longitudinal slats 23 are secured to the bands 20 constituting the top 90 of the sled and a strap 24 having a buckle 25 is arranged on each band 20 under the slats 23. By this arrangement, it will be observed that when the frame of the sled has been collapsed and folded as above described, the foldable top of the sled may be readily folded about said frame and secured in place by means of straps 24 and buckle 25. It will thus be observed that a sled is provided which may be readily collapsed 95 and folded into compact form or readily disengaged in usable form and which is strong and efficient in use.

While I have illustrated and described the preferred form of construction for car- 100 105 110

rying my invention into effect, this is capable of variation and modification without departing from the spirit of the invention. I therefore do not wish to be limited to the 5 precise details of construction set forth, but desire to avail myself of such variations and modifications as come within the scope of the appended claims.

Having described my invention what 10 I claim as new and desire to secure by Letters Patent is:

1. A sled comprising a collapsible frame having runners; transverse flexible straps arranged at the top of said frame, said 15 straps being permanently secured at one side and detachably secured at the other side; and longitudinal supporting slats secured to said transverse straps and arranged to be folded about said frame when collapsed, substantially as described.

2. A sled comprising a collapsible frame having runners; transverse flexible straps arranged at the top of said frame, said 20 straps being permanently secured at one side and detachably secured at the other side; longitudinal supporting slats secured to said transverse straps and arranged to be folded about said frame when collapsed; and means at the opposite ends of said 25 straps for securing said ends together when

said slats are folded about said collapsed frame, substantially as described.

3. A sled comprising a collapsible frame consisting of two side frames, each of said side frames consisting of a top bar and a 35 bottom runner, collapsibly connected together; flexible transverse straps permanently secured to one top bar and detachably secured to the other; longitudinal slats permanently secured to said straps; a buckle at one end of each of said straps; and a strap end at the other end of each strap adapted to engage said buckle, substantially as described.

4. A sled comprising a collapsible frame 45 consisting of longitudinal side bars; runners positioned under said side bars, each runner being connected with a corresponding side bar by a knee-joint; transverse knee-joint members connecting the knee-joints on opposite sides of said frame; and a flexible top extending between said side bars, substantially as described.

In testimony whereof I have signed my name to this specification in the presence of 50 two subscribing witnesses.

MAX BROWN.
